UNITED STATES PATENT OFFICE.

RHEUEL H. FREDERICK, OF IRVINGTON, NEW JERSEY, ASSIGNOR OF TWO-FIFTHS TO CHARLES F. AMES, OF BROOKLYN, NEW YORK, AND ONE-FIFTH TO ALPHONSE H. E. BERCHEM, OF NEW YORK, N. Y.

VACUUM-PRODUCING APPARATUS.

Application filed June 2, 1926. Serial No. 113,308.

This invention relates to vacuum producing apparatus for use more particularly in connection with or as a part of a vacuum steam heating system for the purpose of 5 effecting the removal of fluid accumulations, as air and water, from the radiators and progressively delivering the surplus or accumulated water to a boiler feed-pipe or the like.

10 The object of my invention is to provide an apparatus of simple and durable construction including a novel rotary pump element whereby the kinetic energy of a body of water is efficiently generated by centrifugal force 15 and utilized to create a partial vacuum of high degree which is effective to exhaust from the return of a steam heating system air and water accumulations, and deliver them, entrained with the motive liquid, into 20 a chamber within which the air and non-condensable fluid are separated from the water and permitted to escape, and within 25 which chamber is maintained a uniform volume of water that ensures the sealing of the system, including the pump element.

With this and other objects in view my invention comprises novel features of construction and combinations of parts which will be hereinafter described and claimed.

30 In the drawings—

Figure 1 is a plan of a vacuum producing apparatus embodying a preferred form of my invention.

Fig. 2 is a longitudinal sectional elevation 35 of the apparatus.

Fig. 3 is a transverse vertical section, partly in elevation, as on the line 3—3 of Fig. 1.

Fig. 4 is a longitudinal vertical section of 40 one of the pump units.

Fig. 5 is a transverse section through the pump unit as on the line 5—5 of Fig. 4.

Fig. 6 is a similar section, as on the line 6—6 of Fig. 4.

45 Fig. 7 is a sectional detail, enlarged, of the Venturi nozzle of the vacuum impeller and the diffuser chamber.

Referring to the drawings, 10 designates 50 a horizontally-disposed tank supported by two spaced-apart hollow legs 11, 12 rising from a suitable bed 13. This tank is preferably a cast-iron structure divided into two compartments 14, 15 by means of a vertical

partition or baffle 16 which terminates at a defined level below the top of the tank, as 55 clearly seen in Fig. 2. The compartment 14 constitutes a receiving chamber for the motive liquid and the entrained air, vapors, etc., withdrawn from a vacuum steam heating system, and the compartment 15 constitutes an overflow chamber into which the water contents of the chamber 14 flow as 60 rapidly as the condensate raises the level of the liquid above the top of the baffle. The tank 10 is provided above the chamber 65 14 with an opening 17 having a suitable fitting comprising a water supply pipe 18 and an air vent pipe 19. Preparatory to the operation of the apparatus make-up water is supplied to the tank chambers through the 70 pipe 18 until the contained water is level with the top of the baffle 16. A suitable water gauge 20 is connected with the chamber 15, to indicate the water level in the latter. 75

Each of the legs 11, 12 is provided with a vertical partition 21 to afford two parallel conduits 22, and the bottom of the tank is provided in each compartment with two transversely extending chambers 23 in communication with the respective conduits 22. Each pair of chambers 23 are afforded by an inverted box 24 transversely partitioned at 25, formed in the bottom portion of the tank, one of the side walls of each box 85 24 being provided with ports 26 leading to the respective chambers 23 and having suitable hand-operated valves 27 whereby the ports, or any of them, may be opened or closed, as occasion may require. 90

The tank chambers 14, 15 are independently connected to suitable centrifugal pump units A, B which are mounted on the bed 13, adjacent the respective sides of the tank. These pump units are identical in construction and therefore a description of one will suffice. In the present instance each unit includes two rotary impellers 28, 29 which are fast on a power driven shaft 30 and are rotatable, thereby within two spaced-apart 100 chambers 31, 32 formed in the pump casing 33. The impeller 28 is operative to establish and maintain a continuous circulation of the liquid to and from the receiving chamber and create a sustained vacuum which 105 effects the withdrawal of the accumulations

of air, vapor, etc., from the heating system and their entrainment with the motive liquid in its return to the receiving chamber; and the impeller 29 is operative to withdraw the 5 surplus water continuously from the chamber 15 and deliver it to a boiler feed pipe, as 34.

The impeller chamber 31 is of circular form and the vacuum impeller therein is 10 provided with a central inlet eye 35 and a circumferential Venturi nozzle 36. The inlet eye communicates with an inlet port 37 formed in the casing, which port, in turn, is connected with one of the conduits 22 15 in the adjacent leg 12 by means of a passage 38 which is formed in the bed. Hence when the port in the chamber 23 to which the conduit leads is open, the water contained in the receiving chamber 14 flows 20 directly to the interior of the impeller 28, and is ejected therefrom through the Venturi nozzle 36 in the form of a diverging annulus, as indicated in Fig. 7. Surrounding the circumferential venturi is an annular chamber 39 into which the liquid is 25 forcibly discharged from the impeller nozzle, and in and adjacent the path of this nozzle is a vacuum chamber 40 including ports 41 which are connected with the return 30 line of the heating system by means of a passage 42 formed in the bed. Hence the liquid annulus creates and maintains in the chamber 40 a partial vacuum sufficient to 35 eject air, vapor and water from the heating system, which fluid is entrained with the water entering the chamber 39. This chamber 39 is preferably provided with vanes 420 which are so disposed as to intercept and diffuse the liquids and gases delivered 40 to the chamber, which fluids are thereupon discharged into a volute chamber 43 surrounding the diffuser chamber. The outlet 44 from the volute chamber communicates with a passage 45 formed in an L-shaped 45 conduit 46 connecting the pump casing and one side of the tank, which passage leads to the top of the receiving chamber 14, and discharges the fluid forcibly inward in a horizontal path. The fluid thus discharged 50 strikes a baffle 47 depending from the top of the tank, and is thereby well scattered and diffused upon its delivery to the receiving chamber; the condensable vapors commingling with the water in the tank and 55 the air and non-condensable vapors escaping by way of the vent pipe 19.

In addition to the passage 45 the conduit 46 has two additional passages 48, 49 which afford communication between the tank and 60 the upper ends of two ports 50, 51, respectively, which are formed in the upper part of the casing. These ports communicate at their lower ends with the central inlets (35, 56) of the respective impellers 28, 29 65 and therefore afford vents for the diversion

and escape of the entrained non-condensable gases which would otherwise pass with the liquids into the impellers.

In the present instance, wherein two pump units, each of twin impeller construction, are employed, the passages 42 from the respective pumps lead to a common transverse connecting passage 52 at the end of the bed adjacent the chamber 14, and to this passage is operatively connected, through 70 an interposed combined check valve (53) and strainer structure (54), the return line from the system to be exhausted. As herein illustrated the passage 52 is constituted by the cross-member of a T-fitting to the 75 central member of which the check-valve and strainer structure are connected; the ends of the cross-member having port connections 52' to the respective bed passages 42. Each of the port connections is provided with a hand valve 53' by means of which the adjacent port can be opened or closed at will. One twin impeller pump, (or two single impeller pump units) may be employed, instead of the double twin 80 pump arrangement herein illustrated, and in some installations the vacuum pump may be used independently of the pressure pump.

The impeller chamber 32 in each of the pump casings is of volute form with a suitably located outlet port 55, and the impeller 29, which is mounted in this chamber, is provided with a central inlet eye 56 in communication with an inlet port 57 formed in the casing, which port 57, in turn, is connected with one of the conduits 22 in the adjacent leg 11 by means of a passage 58 formed in the bed. Hence when the port 26 in the chamber 23 to which the conduit leads is open, water flows from the tank 100 chamber 15 to the interior of the impeller 29 and is ejected therefrom into the port 55. This port 55 communicates with a passage 59 formed in the bed 13, which passage is connected with the boiler feed-pipe 105 through a suitably-located T-fitting 60. The cross-member of this fitting is provided at its ends with port connections 61 to the respective bed passages 59, and each connection is equipped with a hand valve 62 by 110 means of which the adjacent port can be opened or closed, at will. The central member of the T-fitting 60 has connected thereto a suitable check valve 63 included in the feed-pipe for the boiler.

Assuming the chambers 14 and 15 of the tank to be supplied with make-up water to the level of the top of the baffle 16, and the ports 26 for the respective bottom chambers 23 to be open, as well as the port connections 52' and 61 for the system return and boiler feed pipe respectively, it will be seen that the impellers of the respective pumps are submerged. Hence when the pumps are actuated the impellers 28 effect a continuous 115 120 125 130 135 140 145 150 155 160 165 170 175 180

circulation of the water contained in the chamber 14, and the impellers 29 effect a sustained withdrawal of the water from the chamber 15. That is to say, the impellers 5 28 withdraw the water from the chamber 14 by way of the adjacent chambers 23, conduits 22, passages 38 and ports 37, and forcibly discharge the water in the form of diverging annuli through the Venturi nozzles of the respective impellers 28. This 10 water passes into the respective diffuser chambers 39 and discharge chambers 43, and returns thence by way of the ports 44 and conduits 45 to the top of the tank chamber 14, where the water impinges against the opposing baffle 47. The energy of the annular walls of liquid in their passage from the Venturi nozzles of the impellers 28 to the diffuser chamber creates and maintains 15 partial vacua in the respective vacuum chambers, the force of which vacua is effective to withdraw the accumulations of air, vapor, etc., from the heating system and cause their entrainment with the liquid flowing 20 to the chamber 14 of the tank, as previously mentioned. The air and non-condensable fluids delivered to this chamber 14 and separated therein from the water escapes through the vent pipe 19 at the top of 25 the tank, while the water of condensation mixes with and variably increases the volume of the liquid contents of the chamber 14, the excess liquid in the latter flowing over the baffle 16 into the chamber 15. This 30 baffle 16 thus ensures a uniform water level in the chamber 15, and in consequence an efficient water seal for the system, including the pumps, is maintained.

The surplus water flowing over the baffle 40 into the tank chamber 15 is constantly withdrawn from the latter by the action of the impellers 29; that is to say, these impellers withdraw the water by way of the adjacent chambers 23, conduits 22, passages 58 and port 57, and forcibly discharge the water 45 into the volute chambers 32 and through the outlet 55 into the passage 59, whence it flows under pressure through the check-valve 63 into the boiler feed-pipe 34.

The effective service of the apparatus can 50 be readily reduced, if occasion requires, by merely stopping one of the pump units A or B and closing the ports 26, 52' and 61 at the side of the tank adjacent the idle pump. In 55 that event the impeller 28 of the active pump unit will function to circulate the water, gases, etc., through the tank chamber 14 and the impeller 29 of such unit will force the water from the other tank chamber 15 to 60 and through the boiler feed-pipe.

I claim—

1. In a vacuum producing apparatus for steam heating systems, the combination with 65 a receiver for motive liquid and condensate, of a pump element including an impeller

chamber, a rotary vacuum impeller therein having a central inlet and a continuous circumferential discharge venturi, a connection affording communication between the receiver and the central inlet, an annular 70 chamber encircling the venturi and spaced therefrom, whereby a diverging annular stream of liquid is forcibly discharged into the said chamber and against the walls thereof, thus producing an ejector effect and a 75 water seal, a vacuum space within which the venturi rotates, said space being in operative communication with the annular chamber and the return line of the steam heating system, and a discharge connection 80 between the said chamber and the upper part of the receiver.

2. In a vacuum producing apparatus for steam heating systems, the combination with 85 a receiver for motive liquid and condensate, of a pump element including an impeller chamber, a rotary vacuum impeller therein having a central inlet and a continuous circumferential discharge venturi, a connection affording communication between the receiver and the central inlet, an annular 90 chamber encircling the venturi and spaced therefrom, whereby a diverging annular stream of liquid is forcibly discharged into the said chamber and against the walls 95 thereof, thus producing an ejector effect and a water seal, spaced apart diffuser blades in said annular chamber, a vacuum space within which the venturi rotates, said space being in operative communication with the annular chamber and the return line of the steam heating system, and a discharge connection 100 between the said chamber and the upper part of the receiver.

3. In a vacuum producing apparatus for 105 steam heating systems, the combination with a receiver and an overflow chamber in communication therewith, of a pump element including a rotary vacuum impeller having a circumferential discharge venturi, an annular 110 chamber encircling the venturi, inlet connections leading from the receiver to the impeller, and discharge connections leading from the annular chamber to the receiver, whereby motive fluid is withdrawn from 115 the receiver by the impeller and forcibly discharged into the annular chamber, a space in which the venturi rotates and in which a vacuum is created by the ejector effect of the liquid discharged from the venturi, a connection between said space and the return of 120 the steam heating system, whereby the force of the vacuum effects the withdrawal of the air and vapors from the system and their entrainment with the discharged motive 125 fluid, a second pump element including a rotary pressure impeller, and operative connections whereby the latter impeller forcibly withdraws liquid from the overflow chamber.

4. In a vacuum producing apparatus for steam heating systems, the combination with a receiver for motive liquid and condensate, of a pump element including an impeller 5 chamber, a rotary vacuum impeller therein having a central inlet and a continuous circumferential discharge venturi, a connection affording communication between the receiver and central inlet, an annular chamber 10 encircling the venturi and spaced therefrom, whereby a diverging annular stream of liquid is forcibly discharged into the said chamber and against the walls thereof, thus producing an ejector effect and a water seal, 15 a vacuum space within which the venturi rotates, said space being in operative communication with the annular chamber and the return line of the steam heating system, a discharge connection between the said 20 chamber and the upper part of the receiver, and vent means between the impeller inlet and the receiver.
5. In a vacuum producing apparatus for steam heating systems, the combination with 25 a receiver and an overflow chamber in communication therewith, of a pump element including a rotary vacuum impeller having a circumferential discharge venturi, an annular chamber encircling the venturi, inlet connections leading from the receiver to the impeller, and discharge connections leading from the annular chamber to the receiver, whereby motive fluid is withdrawn from the receiver by the impeller and forcibly dis- 30 charged into the annular chamber, a space in which the venturi rotates and in which a vacuum is created by the ejector effect of the liquid discharged from the venturi, a connection between said space and the re- 35 turn of the steam heating system, whereby the force of the vacuum effects the withdrawal of the air and vapors from the system and their entrainment with the dis- 40 charged motive fluid, a second pump element including a rotary pressure impeller, opera- 45 tive connections whereby the latter impeller forcibly withdraws liquid from the overflow chamber, and vent means between the respective impeller inlets and the receiver.
6. In a vacuum producing apparatus for steam heating systems, the combination with a receiver and an overflow chamber in communication therewith, of a pump element including a rotary vacuum impeller having a 50 circumferential discharge venturi, an annular chamber encircling the venturi, inlet connections leading from the receiver to the impeller, and discharge connections leading from the annular chamber to the receiver, 55 whereby motive fluid is withdrawn from the receiver by the impeller and forcibly dis- 60 charged into the annular chamber, a space in which the venturi rotates and in which a vacuum is created by the ejector effect of the liquid discharged from the venturi, a

connection between said space and the return of the steam heating system, whereby the force of the vacuum effects the withdrawal of the air and vapors from the system and their entrainment with the discharged motive fluid, a second pump element including a rotary pressure impeller, operative connections whereby the latter impeller forcibly withdraws liquid from the overflow chamber, vent means between the respective impeller 70 inlets and the receiver, said vent means and the discharge connections from the annular chamber including a structure having a discharge passage and two independent vent 75 passages extending therethrough.

7. In a vacuum producing apparatus for steam heating systems, the combination with a receiver for motive liquid and condensate, of a pump element including a rotary vacuum impeller having a central inlet eye and a contracted circumferential outlet, an inlet port in connection with said eye, a vent port in communication with the inlet port and with the upper part of the receiver, an annular chamber encircling the said impeller and spaced therefrom, a vacuum space within which the circumferential outlet rotates, a bed upon which the pump element is mounted, a leg rising from said bed and supporting the receiver, said leg having a 80 conduit therein leading to the receiver, and said bed having therein two passages, one of which connects the leg conduit with the said inlet port, and the other of which passages connects the vacuum space with the return 85 line of the heating system, an annular chamber encircling the circumferential outlet of the impeller and spaced therefrom, and a discharge connection between said chamber 90 and the upper part of the receiver.

8. In a vacuum producing apparatus for steam heating systems, the combination with a receiver for motive liquid and condensate, of a pump element including a rotary vacuum impeller having a central inlet eye and a contracted circumferential outlet, an inlet port in communication with said eye, an annular chamber encircling the said impeller and spaced therefrom, and a vacuum space within which the circumferential outlet 100 rotates, a bed upon which the pump element is mounted, a leg rising from said bed and supporting the receiver, said leg having a conduit therein leading to the receiver, and said bed having therein two passages, one of which connects the leg conduit with the said inlet port, and the other of which passages connects the vacuum space with the return 105 line of the heating system, an annular chamber encircling the circumferential outlet of the impeller and spaced therefrom, and a discharge connection between said chamber 110 and the upper part of the receiver.

9. In a vacuum producing apparatus for steam heating systems, the combination with 115

- a receiver for motive liquid and condensate, and an overflow chamber in open communication with said receiver at a defined water level, of a pump element including an impeller chamber, a rotary vacuum impeller therein having a central inlet eye and a contracted circumferential outlet, an inlet port in communication with said eye, an annular chamber encircling the said impeller and spaced therefrom, a vacuum space within which the circumferential outlet rotates, a bed upon which the pump element is mounted, a supporting leg rising from said bed and having a conduit therein leading to the receiver, said bed having therein two passages, one of which connects the leg conduit with the said inlet port, and the other of which passages connects the vacuum space with the return line of the heating system, an annular chamber encircling the circumferential outlet of the impeller and spaced therefrom, a discharge connection between said chamber and the upper part of the receiver, a second pump element including an impeller chamber, a rotary pressure impeller therein having a central inlet eye and a circumferential discharge outlet, an inlet port in communication with the latter eye, an outlet port from the latter impeller chamber, a second supporting leg rising from said bed and having a conduit therein leading to the overflow chamber, said bed having two additional passages whereof one connects the second leg conduit with the inlet port for the pressure impeller and the other of which passages constitutes a discharge from the outlet port. 10. In a vacuum producing apparatus for steam heating systems, the combination with the receiver for the motive liquid and condensate, of a plurality of impellers, means for rotating said impellers, one of said impellers having a connection for delivering the return liquid from the system to the receiver through an annular nozzle directed into a chamber surrounding the nozzle in communication with the receiver, a vacuum chamber at each side of the nozzle in communication with the return from the system and from which air and vapor are drawn by the nozzle into the first mentioned chamber, connections between the second impeller and the receiver, and a connection between the second impeller and the feed side of the system for drawing water from the receiver and delivering it to the system. 15 20 25 30 35 40 45 50 55

Signed at New York in the county and State of New York this 28th day of May, A. D. 1926.
